CLAIM

The ornamental design for a tracker housing as shown and described.

DESCRIPTION

FIG. 1 is a top, right, front perspective view of a tracker housing showing the new design;

FIG. 2 is a bottom, left, rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof;

FIG. 9 is a cross-section view thereof, taken along line 9-9 in FIG. 3; and,

FIG. 10 is a cross-section view thereof, taken along line 10-10 in FIG. 5.

The dashed lines shown in the drawings illustrate portions of the tracker housing that form no part of the claimed design.

1 Claim, 10 Drawing Sheets
